UNITED STATES PATENT OFFICE.

CYRUS CRABBS, OF TORONTO, CANADA.

FENCE.

SPECIFICATION forming part of Letters Patent No. 447,539, dated March 3, 1891.

Application filed October 10, 1889. Serial No. 326,599. (No model.)

To all whom it may concern:

Be it known that I, CYRUS CRABBS, a subject of the Queen of Great Britain, residing at Toronto, in the Province of Ontario and 5 Dominion of Canada, have invented certain new and useful Improvements in Fences, of which the following is a specification.

The principal object of my said invention is to produce a fence which shall be strong 10 and durable and so firmly anchored to position as to resist any force likely to come against it and such as is liable to overthrow ordinary fences. This object is accomplished by a certain construction and arrangement of 15 the several parts in relation to each other and the securing of them together, as will be hereinafter more particularly described and claimed.

Referring to the accompanying drawings, 20 which are made a part hereof, and on which similar letters of reference indicate similar parts, Figure 1 is a perspective view of a section of rail fence embodying my said invention; Fig. 2, a horizontal sectional view looking downwardly from the dotted line 2 2 in 25 Fig. 1; Fig. 3, a transverse sectional view looking toward the left from the dotted line 3 3 in Fig. 1, and Fig. 4 a detail view showing the method of attaching and fastening 30 the rails to the posts.

In said drawings, the portions marked A represent vertical fence-posts; B, the ordinary rails; C, the rider-stakes, and D the rider-rails.

35 The posts A are simply straight upright posts set in the ground in the ordinary and well-known manner, and to these rails, boards, or other devices forming the fence are attached. The ends of the rails composing the 40 adjacent lengths of the fence are preferably arranged on opposite sides of the post, as shown, the post being thus arranged centrally in relation to the weight supported.

The rails B (when rails are used) are secured to the posts A by first holding them in the position shown in Fig. 4, passing a strong wire *a* around the post and the rail and securing the ends firmly together, and then bringing the rail down to a horizontal position, as shown in Fig. 1, which has the effect 50 to sink the wire into the wood of the post and the rail and to hold the rail in a secure man-

ner upon said post. At the second post the process is the same, except that the wire is passed around the ends of two rails, (one upon each side of the post,) one of the rails only being inclined upward, the other being the one which has already been attached to the preceding post. This process is continued to any length desired and to the height to 60 which the fence is to be built, lacking only the top or rider rail. While these rails, as shown, contribute to a desirable form of fence, other forms of rails, bars, boards, wires, or other devices may be used in connection with 65 my improved rider-rail construction without departing from that portion of my invention.

The rider-stakes C are driven into the ground in the ordinary manner and cross above the top one of the rails B, already in 70 position, resting on top of the vertical post A alongside the posts, as shown.

The rider-rails D are like ordinary rider-rails, except that they are made tapered or wedge-shaped at the point where they come 75 in contact with the rider-stakes so as to fit closely against said stakes. They are then driven down tightly between the stakes, so as to bind tightly between them, and a wire *c* is then passed around said stakes and said 80 rails, as shown, tying the rails down to the position to which they have been driven. A second wire *d* is then tied around the rider-stakes under the next rail below the rider-rail, which hold said stakes still more firmly 85 together.

A fence constructed in this manner, by reason of the driving or forcing of the rider-rails down firmly between the stakes and the securing of said rails in that position, is very 90 strong and durable. By actual test I have found that such a fence cannot be overthrown by the best efforts of a team of horses, while fences as ordinarily constructed not locked in position are liable to be overthrown by 95 high winds and by breamy or unruly animals.

Having thus fully described my said invention, what I claim as new, and desire to secure by Letters Patent, is—

The combination, in a fence, of the vertical 100 post A, arranged centrally in relation to the weight supported thereby, the rails B, secured to opposite sides thereof, except the top one, which rests on the top of said post and under

the rider-stakes, said rider-stakes arranged in pairs which straddle said main part of the fence above said top rail at both its ends, and the rider-rails D, arranged between the upper 5 ends of said rider-stakes vertically above the rails which rest on top of the posts A, the whole being secured together by wires, substantially as set forth.

In witness whereof I have hereunto set my hand and seal, at Indianapolis, Indiana, this 30th day of September, A. D. 1889.

CYRUS CRABBS. [L. S.]
